UNITED STATES PATENT OFFICE.

JACOB H. BRUBAKER, OF ROCKTON, PENNSYLVANIA.

ANIMAL-TRAP.

SPECIFICATION forming part of Letters Patent No. 279,126, dated June 12, 1883.

Application filed March 2, 1883. (No model.)

To all whom it may concern:

Be it known that I, JACOB H. BRUBAKER, a citizen of the United States, residing at Rockton, in the county of Clearfield and State 5 of Pennsylvania, have invented certain new and useful Improvements in Animal-Traps; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to improvements in "snares" or traps to capture destructive birds—as, for instance, crows, hawks, and such like—and plundering animals—as bears, &c.; and it consists in the combination and arrangement of parts, substantially as hereinafter more 20 fully set forth and claimed.

In the accompanying drawings, Figure 1 is a perspective view, and Fig. 2 is a vertical section, of my improved animal-trap. Fig. 3 is 25 also a vertical section of a modification of the same.

In putting my invention into practice I employ a post, A, which is constructed with a chamber, *a*, in the lower part, as clearly seen 30 in Fig. 2.

B is a platform arranged above the post, and having a standard or rod, *b*, fixed to its lower side, said standard reaching down through a channel or passage, *b'*, in the post into the 35 chamber *a* thereof, where it is adapted to be supported upon one end of a notched lever, C. Said lever is pivoted near its notched end to the post A, said end thereof being engaged by a pawl or detent, *c'*, also pivoted to 40 the post.

D are a number of springs or elastic rods, secured to the upper end of the post and extending up around the platform B, a short distance above the same, said rods having outwardly-bent portions or stops *d*.

E is a rope or wire, with one end adapted to be looped around the upper ends of the rods or springs D, being held from sliding down

too far thereon by the stops or projections *d* of the latter, and passed through the apertured 50 plate *e*, fixed to the post, while its other end is connected to the forward end of a spring, F, arranged at one side of the chamber *a* and adapted to extend thereinto and beyond the same, and rest against the under side of the 55 detent *c*, where the rope or wire is attached to it. A spring-pawl and ratchet, *f f'*, prevent the uncoiling of the spring F from the recoil action of the spring when the trap is "sprung." The end of the spring to which the wire or 60 rope is secured is apertured to permit the connection of the same to the under side of the detent *c*, which has a pin or projection, *g*, to enter the aperture of the spring, as clearly shown.

65 In lieu of the coiled spring, a weight, as shown in Fig. 3, may be used for "springing" the trap.

It will be seen that should a bird, such as before-mentioned, alight or an animal step 70 on the platform B, the weight of the former or the pressure of the paw of the latter will force the platform downward, and thus trip the lever C, when the recoil action of the spring or the descent of the weight will cause 75 the sudden drawing of the loop of the wire or rope off the spring-rods and partly through the apertured plate. The effect of this action of parts, it is obvious, will be to draw the loop tightly around the leg of the bird or animal, 80 so as the case may be, and thus secure or capture it.

Of course the capacity and stability of the trap are to be governed according to the class of service it is to perform, whether it is to be 85 used to capture birds or animals.

I do not confine myself to the exact form or proportion of parts, as I am aware that the same can be changed without departing from the spirit or sacrificing the advantages of 90 my invention.

I claim and desire to secure by Letters Patent—

1. The combination of a platform mounted upon a rod or standard, the lower end of 95 which rests upon a notched lever, a pawl, a

wire or rope, a series of springs, and means for withdrawing the wire from the springs, as and for the purpose set forth.

2. The combination of a platform mounted upon a rod or standard, the lower end of which rests upon a notched lever, a pawl, a wire or rope, an apertured plate, a series of springs having stops to support the wire, and

means for withdrawing the wire from the springs, as and for the purpose set forth. 10

In testimony whereof I affix my signature in presence of two witnesses.

JACOB H. BRUBAKER.

Witnesses:

CHARLES COLDWELL,
G. H. COLDWELL.
